UNITED STATES PATENT OFFICE.

EVERETT N. MURPHY, OF CHICAGO, ILLINOIS, ASSIGNOR TO STEVENS PARTITION & FLOOR DEADENER COMPANY, OF CHICAGO, ILLINOIS, A CORPORATION OF ILLINOIS.

WALL CONSTRUCTION.

Application filed September 22, 1924. Serial No. 738,983.

This invention relates to sound proofing, and more particularly to an improved method of and means for sound proofing partitions and walls whereby the transmission of sound vibrations from room to room is effectively prevented.

One of the objects of my invention is to provide a construction which will be efficient, durable, light, and cheap, and which can be quickly installed. Further objects will appear from the following detailed description.

In the drawings, in which several embodiments of my invention are shown:

15 Figure 1 is a vertical cross sectional view through one side of a room illustrating one of the embodiments of my invention, having the finishing walls, ceiling and floor in sound proof relation with the inner supporting structure;

Fig. 2 is a disassembled view of sound insulators I employ in sound proofing partitions;

Fig. 3 is a face view of the side wall, with portions broken away to show the construction;

Fig. 4 is a detail sectional view of one of the wall insulators, taken on line 4—4 of Fig. 1;

30 Fig. 5 is a similar view taken on line 5—5 of Fig. 8, but with the section taken at right angles to Fig. 3;

Fig. 6 shows a detail of the face of one of the insulators;

35 Fig. 7 is a view similar to Fig. 1 but illustrating a different form of inner supporting structure;

Fig. 8 is a horizontal cross sectional view of a thin partition which is sound proofed in a manner similar to that of Fig. 1;

40 Fig. 9 is a view similar to Fig. 8 but illustrating a form of inner supporting structure and sound proofing means which permit the finishing wall of a partition to be spaced apart a minimum distance; and

45 Fig. 10 is a still further disclosure of disposing the sound insulating means between the finishing walls of a partition.

Building construction invariably differs.

50 Each building is designed according to the particular use to which it will be put or to the particular needs of the owners. Some buildings are fire proof, others are not. Hence,

it will be noted that the inner supporting structure of the finishing wall will, in many cases, be different. My invention is capable of embodiment in buildings having these different inner supporting structures inasmuch as the fundamental principle of breaking the solids between walls may be employed in a variety of ways, and my improved sound insulating means, or "sound insulators" may be used to hold the walls apart in such relation.

I shall describe a number of such embodiments, one of which may be used where the inner supporting structure is either that of an outside wall of the building, or the supporting structure of an inner wall of the building. Another embodiment is where the finishing walls of the lath and plaster of adjacent rooms are spaced apart, and the inner supporting structure serves as the means of carrying my improved sound insulating means between the walls. In another embodiment, the distance between walls is taken into consideration for the sake of economy, and consequently, this inner supporting structure is such that these finishing walls are brought together a minimum distance. I shall now describe these embodiments and my improved sound insulating means.

The sound insulated partition illustrated, particularly in Fig. 1 of the drawings, comprises an inner supporting wall or structure 2 and a facing or finishing wall 3, both of which are spaced apart in sound proof relation by a plurality of sound insulators 4. The inner supporting structure 2 may be of tile, as illustrated in this figure, or it may be of any other well known construction.

Insulators 4, illustrated in an exploded view in Fig. 2, serve to break contact between the solids of these walls and provide a sound-proof non-vibratory transmitting contact, whereby neither sound nor vibrations may travel from wall to wall. This is accomplished by furnishing the insulators 4 in the form of cushioning members provided with sound or vibration absorbing means, so that there will be no direct solid contact between the parts. It will be remembered that these insulators 4 may be of a design different from that shown, but in their preferred form they may be furnished with a

plate 6 having laterally turned sides 7, which form socket-like or cup-shaped members. These members are adapted to receive an interior lining of felt or cattle hair 8 in the form of a pad conforming to the inner configuration of the members. A U-shaped strip 9 is inserted in the felt pad 8 and a second felt pad 10 is placed therein. A rivet 11 then extends centrally through these parts (including said felt pads 8 and 10), one end of which rivet may be riveted over or otherwise suitably held in plate 6, as indicated at 12, while the opposite end may be provided with a head 13 for holding washer 14 on the rivet.

Strip 9 may be apertured at 15 to permit rivet 11 to pass therethrough, the aperture, however, being of such size as to prevent contact between the strip and the rivet. The rivet 11 is permitted, however, to have slight freedom of movement at each end in order to allow relative movement between the two parts of the insulators 4, caused by vibration in the walls in a direction not parallel to rivet 11. This flexibility in the construction of each insulator is desirable, because it serves to check transmission of this relative movement or vibration between walls. For the vibration parallel to the rivet 11, the middle portions of pads 8 and 10 serve as the absorbing medium. Vibration in this direction is, likewise, not transmitted through the rivet 11, due to the latter's non-solid contact with the strip 9, and also to the fact that plate 14 is maintained in spaced relation with the strip 9 by the sides 16 of the pad 10.

Pad 8 serves to embrace the strip 9, so that movement of the member 6 in any direction, as the result of the facing or finishing wall 3 vibrating, will not destroy the sound proof or non-vibration transmitting contact between these parts 9 and 6. The latter are held together in this relation by rivet 11, and pad 10 serves, in one respect, to hold the rivet out of direct physical contact with strip 9, in order to maintain broken contact between solids.

The facing or finishing wall, illustrated in Fig. 1, is of relatively simple construction, comprising essentially upright channel irons 18, to which metal lathing 19, or the like, may be attached, and a coat of wall plaster 20 laid on the lathing 19. This construction is somewhat optional and may be changed without departing from the scope of the present invention.

Referring to Fig. 6, plate 6 is provided with a pair of lugs 21 which are struck outwardly therefrom and are disposed on opposite sides of the apertures through which rivet 11 passes. As illustrated in Fig. 4, these lugs 21 are spaced to lie on opposite sides of each channel iron 18. A wire 22, or like tying member, may pass through

openings 24 in plate 6 and around the lugs 21 and channel iron 18 to tie the same together. Thus the insulators may be fastened to the facing or finishing wall 3, the plate 6 having the solid contact with the wall.

The fire proof tile wall 2 or inner supporting structure of Fig. 1 is common in fire proof buildings. In the present disclosure, vertical bars 25 may be secured thereto in any suitable manner, say by toggle bolts 26.

Strips 9 of each insulator 4 may be furnished with feet 27 adapted to be suitably secured to vertical bars 25 at 28. This constitutes the solid contact between the inner supporting structure 2 and the insulator 4, it being noted, moreover, that this solid contact is only with the strip 9.

The floor construction shown in Fig. 1 comprises the lower rough floor 30 supported in any suitable manner, and upper finishing floor 31 secured to a nailing strip 32, supports or chairs 33 on which the nailing strip 32 is supported, and a pad or cushion 34 embracing the nailing strip 32 and held in place by the chairs 33.

Channel irons 18 may rest on a pad or cushion 34 which is held in place by means of a chair 35 corresponding somewhat to the chairs 33. Chair 35 comprises a cushion-holding portion 36 and a pair of spaced legs 37, which bear on the lower floor 30, to which they are secured by suitable securing means 38. As illustrated in Fig. 3, insulators 4 are provided spaced apart in rows, each row being fastened to a channel iron 18. In assembling these channel irons 18, the lower ends are bolted to a horizontally disposed bar 39 adapted to be seated in the cushions 34. With this construction, it will be noted that there is no rigid connection between the supports for the lath and plaster and the rough floor 30, the only connection being through the cushions 34. By this construction various advantageous features are obtained. The complete isolation of the wall or partition from the lower floor may be obtained, that is, the nails or other securing means do not extend through the cushions so as to connect the parts mechanically.

The ceiling construction of the embodiment comprises a sound insulated structure, also preventing the transmission of sound or vibration to or from the floor above. A plurality of horizontally disposed stringers in the form of channel irons 40, similar to the vertical channel irons 18 of the facing or finishing wall 3, and provided in two rows, one above the other, and at right angles to each other, comprise the part to which the lath 41 may be fastened, the lath being secured preferably to the lower row. The channel irons 40 of this lower row have their outer ends suitably secured to the adjoining upper ends of the vertical channel irons 18.

say by tying as indicated at 42 in Fig. 1. A coat of plaster 43 is laid on the lath 41.

A plurality of cushioning supports 45 is provided for suspending the ceiling construction in sound proof and non-vibratory transmitting relation. Supports 45 may be formed of U-shaped pad rests 46, having upwardly extending apertured flanges 47 adapted to be suspended from the floor above by suitable securing means 48. Pads 49 of cattle hair or felt seat in the pad rests 46, the bottom portion of the latter being apertured at 50 to permit the shanks 51 of hooks 52 to extend upwardly, so that the heads 53 of shanks 51 hold the inverted transversely extending U-shaped straps 54 in a straddled position across the pads 49 and pad rests 46. It will be noted that solid contact exists between hooks 52 and inverted U-shaped straps 54, but that these straps 54 are out of contact with the pad rests 46, except through the pads 49. Hooks 52 are looped about the upper row of the horizontal channel irons 40 for supporting this portion of the ceiling construction. It will further be noted that the upper and lower rows of these horizontal channel irons 40 are, of course, suitably secured to each other, as for instance, by tying, indicated at 53'.
 For preventing the transmission of sound and vibration across the space between the inner supporting structure 2 and the finishing or facing wall 3, and also across the space between the ceiling construction and the floor above, these spaces are provided with layers or quilts 55 and 56, respectively, of cattle hair, felt, or like material. It will be noted in Fig. 1 that these quilts 55 and 56 overlap at their adjoining ends whereby these spaces are disconnected or separated from each other to prevent sound or vibration in either space from being transmitted to the other. I have found that these quilts tend to absorb sound-vibration and prevent its "rebound" between the inner supporting structure and finishing wall of the partition, the same effect also taking place between the ceiling construction and floor above. The space between the finishing floor 31 and lower floor 30 may be filled with a dry, cellular, fire proof aggregate, such as dry cinders. This prevents all of the above three spaces from acting as resonating chambers to produce what is known as a "drum effect."

Quilt 55 may be laid against the side of the inner supporting structure 2 and the toggle bolts 26 allowed to pass through the same, thereby permitting the vertical bars or members 25 to serve the dual function of holding the quilt 55 in position and also of retaining the U-strips 9 against the inner wall 2. Quilt 56 may be placed across the horizontal channel irons 40 in any suitable manner.

In the embodiment of my invention illustrated in Fig. 7, the inner supporting structures of the wall and the ceiling are also of a well known construction and are usually employed in non-fire proof structures. The inner supporting structure of the wall comprises the usual studding 65, preferably of 2 x 4 inch boards suitable spaced apart on centers, for receiving the sound insulating means embodying my invention. In this instance the insulators 4 are practically of the same construction, as heretofore described, except for the rivets 11, which hold plates 6 and strips 9 together in non-solid contact, with the sound insulating pads 8 and 10, properly interposed. Bolts 66 are substituted for the rivets 11, functioning the same as the latter, but permitting the vertical members 67, to which the lath and plaster are fastened, to receive the heads of the bolts. Nuts 68 on the opposite end of bolts 66 allow the parts 6 and 9 to be drawn as close together as desired. Feet 27, of part 9 of each insulator 4, may be secured to the studding 65 by nails 69, or the like.

The inner supporting structures of the ceiling of this embodiment comprise a rough floor 70 fastened to joists 71 spaced by bridging 72. To the lower side of the joists 71, the furring strips 73 are nailed. In this instance, the insulators 4 are laid flatwise and the feet 27 of each insulator are fastened to the furring strips 73. Bolts 66 are permitted to extend downwardly through apertured purlin 75 laid upon transverse channel-irons 76. It will be noted that the lath and plaster of the ceiling are fastened to the channel irons 76. The "drum effect" between the inner supporting structures of the wall and ceiling and the finishing wall and finishing ceiling, due to the sound rebounding in the spaces therebetween, is prevented by quilts 78 and 79, respectively, of cattle hair, felt, or like material, which tend to absorb the sound. The quilts may be continuous with respect to each other, if so desired, and fit tightly in the upper corners where the inner supporting structures of the wall and ceiling meet. Quilts 78 and 79 are held against the studding 65 and the furring strips 73 by the nails passing through the feet 27 and securing the insulators 4 in place.

In this embodiment of my invention, the floor may be of the same construction as previously described.

In connection with the embodiments of my invention just described, it will be observed that with the sound insulators 4 used in the manner shown, in partitions and ceilings, having the inner supporting structure described, a very compact sound deadening structure may be realized.

An even more compact arrangement is illustrated in Fig. 8 wherein the facing or

finishing walls are spaced closer together well as any of the other embodiments described, the sound insulating or proofing means are so arranged with respect to the inner supporting structures that the solids between the walls are broken.

I preferably provide a plurality of channel members 59 which are adapted to receive the furring 58. Insulators 4 may be fastened in practically the same manner as before described, that is, each strip 9 may be arranged to have its feet 27 lying against the member 59, and be secured thereto, as indicated at 60 in Fig. 5. The quilt in this instance, is wound in a zig-zag manner about the furring 58, so that it may be attached by the nails 61 to the sides of the strips opposite the insulators. Thus the quilt forms a continuous sound insulation barrier in the space between the facing walls and prevents the so-called "drum effect" hereinbefore mentioned.

In Fig. 9 I have illustrated an embodiment affording still further compactness of the sound deadening and inner supporting structure. The structure shown is used chiefly for inside partitions of buildings. The finishing walls 80 and 81 are walls of adjoining rooms and are spaced apart a minimum distance. Vertical channel irons 84 may be provided to receive the feet 27 of part 9 of each insulator 4. The opposite sides of the insulators are secured to members 85 by means of bolts 86, which are similar to the rivets 11 or bolts 66 of the embodiments hereinbefore described. A quilt 87 of felt, cattle hair or the like, for preventing a "drum effect" of and tending to absorb the sound vibrations between walls 80 and 81 is passed between these walls, being fastened to the channel irons 84 by bolts 88, which draw the quilt tightly into the channels.

It will be noted that the insulators 4 are disposed in vertical rows which alternate in their position with respect to the walls 80 and 81. Thus these walls may be brought as close together as possible and supported with maximum efficiency by a minimum number of sound insulators 4.

In Fig. 10, a sound proof construction is illustrated which has the opposed finishing walls 90 and 91 of a partition fastened to the opposite sides of the insulators 4. The lath and plaster of wall 90 are secured to vertical channel irons 92 preferably by means of bolts 93 which secure in position the feet 27 of part 9. The lath and plaster of wall 91 are secured to vertical channel irons 94, preferably by means of a bolt 95 which is similar to the bolt 86 of Fig. 9. A quilt 96 for preventing the "drum effect" of the sound vibrations in the space between these walls is passed between each insulator 4 and the iron 94.

In this embodiment of my invention, as

described, the sound insulating or proofing means are so arranged with respect to the inner supporting structures that the solids between the walls are broken.

While I have illustrated a plurality of embodiments of my invention, it is apparent that many modifications therein may occur to those skilled in the art. I desire, therefore, that my invention be limited only by the scope of the prior art or by the statements of the appended claims.

I claim:

1. Sound proofing means for a building partition comprising a member adapted to be fastened to an inner supporting structure, a cooperating member adapted to be secured to a facing or finishing wall, cushioning means arranged between said members whereby the latter are held out of solid contact with each other, and interconnecting means for said members.

2. Sound proofing means for a building partition comprising a member adapted to be fastened to an inner supporting structure, a cooperating member adapted to be secured to a facing or finishing wall, cushioning means arranged between said members whereby the latter are held out of solid contact with each other, and interconnecting means for said members, said interconnecting means being in solid contact with one of said members.

3. Sound proofing means for a building partition comprising a plurality of unitary elements spaced at predetermined distances for holding a facing or finishing wall out of physical contact with an inner supporting structure or wall, said elements cushioning or absorbing sound vibration in all directions in the plane of the wall and having means to prevent its transmission in a plane transverse to the wall.

4. Sound proofing means for a building partition comprising a plurality of unitary cushioning elements for holding a facing or finishing wall out of solid contact with an inner supporting structure or wall, said elements serving to cushion or absorb sound vibration in all directions in the plane of the wall.

5. In a building construction, the combination of an inner supporting structure or wall, a facing or finishing wall, means for breaking the solids of said walls whereby sound and vibration transmission is effectively prevented, said means comprising sound insulators spacing said walls apart, said sound insulators including a pair of interconnected cooperating members and a cushioning pad serving as the only physical contacting element between said members.

6. In a building construction, the combination of an inner supporting structure or wall, a facing or finishing wall, sound insu-

lating means for spacing said walls apart, said sound insulating means adapted to break the interconnecting solids of said walls to prevent sound transmission there-
 5 between, said means comprising rigid members attached to the inner wall, cushion retaining members provided with sides for embracing said rigid members, a plurality of cushion pads between said member, and
 10 means for interconnecting said members together with the cushion pads interposed.

7. In a building construction, the combination of an inner supporting structure or wall, a facing or finishing wall, sound insu-
 15 lating means for spacing said walls apart and breaking the solids between walls to prevent sound and vibration transmission, said sound insulating means comprising co-
 20 operating members, one of which is rigidly fixed to one wall and the other of which is fastened to the other wall, a cushion pad between said cooperating members, and means for interconnecting and permitting relative movement between said cooperating

25 members without destroying or impairing the non-vibration transmitting contact therebetween, said cushion pad serving as the only physical contact between these said members.

30 8. In a building construction, the combination of an inner supporting structure or wall, a facing or finishing wall, sound insulating means for breaking the solids between walls to prevent sound transmission, said

35 sound insulating means comprising a rigid member fixed to said inner wall, and a co-
 40 operating cushion retaining member movable with said facing or finishing wall when the latter is vibrated by sound waves strik-
 45 ing thereagainst or transmitted thereto, a cushioning pad interposed between said rigid member and said cooperating cushion retaining member, said cushioning pad serving as the only physical contact between these said members, and an interconnecting element for said members.

9. In a building construction, the combination of an inner supporting structure or wall, a facing or finishing wall, sound insu-
 50 lating means for spacing said walls apart, said sound insulating means comprising a pair of centrally aligned members, one of which is adapted to embrace the other, cushioning pads interposed between said mem-
 55 bers, and an element for interconnecting said members without destroying or impairing the physical contact furnished only by said cushioning pads between these mem-
 bers.

60 10. In a building construction, the combination of an inner supporting structure or wall, a facing or finishing wall spaced there-
 65 from including furring strips, lathing se-
 cured to said furring strips and a coat of

connecting said walls comprising a rigid member fixed to the inner wall and a second member embracing at least a portion of said rigid member, sound cushioning means be-
 70 tween said members, an interconnecting ele-
 ment for said members, and means for con-
 necting said second member to said furring strips.

11. In a building construction, the combi-
 75 nation of an inner supporting structure or wall, a facing or finishing wall spaced there-
 from including furring strips, lathing se-
 cured to said furring strips and a coat of
 80 plaster on said lath, sound insulators for
 connecting said walls comprising a rigid
 member fixed to the inner wall and a second
 member embracing at least a portion of said
 85 rigid member, cushioning means between
 said members, an interconnecting element for
 said members, and means for connecting said
 second member to said furring strips, said
 90 means also being arranged to pass through
 and to hold said lath against said furring
 strips.

12. In a building construction, the combi-
 95 nation of an inner supporting structure or wall, a facing or finishing wall, sound
 insulators between said walls comprising aligned apertured members, a cushioning
 pad interposed between said members, said
 cushioning pad serving as the only physical
 contact between said members and also be-
 100 tween said walls, an interconnecting element
 for passing centrally through the apertures
 of said members, a plate adjacent one end
 of said element, and a second cushioning pad
 between said plate and the other member.

13. In a building construction, the combi-
 105 nation with a structure including two walls,
 of sound insulators between said walls, each
 including a pair of members and a pair of
 cushioning pads, one of which pads may be
 interposed between said members, an ele-
 110 ment for interconnecting said members in a
 manner to permit movement of one member
 against the other member by the vibration
 of either wall, a plate-like member at one
 end of said element, the other of said pads
 115 being interposed between said plate and one
 of said members.

14. Means for spacing a facing or finish-
 ing wall from an inner supporting struc-
 ture or wall in sound proofing relation com-
 120 prising a pair of relatively movable cooper-
 ating cushion retaining members, cushioning
 pads for said members, and an intercon-
 nection between said members and said cushioning
 pads whereby the vibrating move-
 125 ment of said facing or finishing wall in a
 plurality of directions will be absorbed by
 said cushioning pads.

15. In a building construction, the combi-
 130 nation of an inner supporting structure or
 wall, a facing or finishing wall spaced there-
 from, sound insulating means between said

- walls, said sound insulating means functioning to prevent transmission of sound through the solids of these walls and also through the air-space between the walls, said means comprising units connecting the facing or finishing wall to the inner wall but providing non-vibration transmitting contact therebetween, a layer of sound absorbing material between said walls so as to prevent a continuous air-space from one wall to the other, and means for fastening said sound absorbing material in position.
16. In a building construction, the combination of an inner supporting structure or wall, a facing or finishing wall spaced therefrom, sound insulating means between said walls, said sound insulating means functioning to prevent transmission of sound through the solids of these walls and also through the air-space between the walls, said means comprising units connecting the facing or finishing wall to the inner wall but providing non-vibration transmitting contact therebetween, a layer of sound absorbing material between said walls so as to prevent a continuous air-space from one wall to the other, and means for fastening said material in position, said means comprising a plurality of spaced strips secured to and holding said material against said inner wall.
17. In a building construction, the combination of an inner supporting structure or wall, a facing or finishing wall spaced therefrom, sound insulating means between said walls, said sound insulating means functioning to prevent transmission of sound through the solids of these walls and also through the air-space between the walls, said means comprising units connecting the facing or finishing wall to the inner wall but providing non-vibration transmitting contact therebetween, a layer of sound absorbing material between said walls so as to prevent a continuous air-space from one wall to the other, and means for fastening said material in position, said means comprising a plurality of spaced strips secured to and holding said material against said inner wall, and fastening means for attaching said units to said strips.
18. In a building construction, the combination of an inner supporting structure or wall, a facing or finishing wall spaced therefrom, a lower floor, sound insulating means between said walls, said sound insulating means functioning to prevent transmission of sound through the solids of these walls and also through the air-space between the walls, said means comprising units connecting the outer wall to the inner wall but providing non-vibration transmitting contact therebetween, a layer of sound absorbing material between said walls so as to prevent a continuous air-space from one wall to the other, means for fastening said material in position, and sound insulating means for supporting said outer wall upon said lower floor.
19. In a sound proofing building construction art, the combination of a room provided with its finishing floor out of physical contact with the walls, a lower floor, cushioning means resting on said lower floor for supporting said finishing floor in sound proof relation, and cushioning means also resting on said lower floor for supporting said walls in sound proof relation with respect to said lower floor and for holding the same out of physical contact with said finishing floor.
20. A sound proofing structure for a building partition, comprising the combination with a plurality of cushioning elements for normally breaking solid contact between opposed finishing walls and an inner supporting structure, of means associated with said cushioning elements for anchoring said opposed walls to said inner supporting structure without destroying the sound proof relation provided by said cushioning elements.
21. In a building construction, the combination with a finishing wall and the structure of the building to which said finishing wall is attached, and sound insulating means between said finishing wall and said structure, of means for anchoring said finishing wall to said structure, said anchoring means preventing movement of the finishing wall beyond that which will be absorbed by said sound insulating means during vibration.
22. In a building construction, the combination of a partition, a finishing wall therefor, and sound insulating means for supporting said finishing wall, said sound insulating means including a layer of sound insulating material and cushioning elements serving to anchor the finishing wall to said structure.
23. In a building construction, the combination of a floor and a partition of a room, a finishing wall for said partition and resting on said floor, and sound insulating means for supporting said finishing wall upon said floor and against said partition, and a layer of sound insulating material between said partition and said finishing wall.
24. In a building construction, the combination with an inner wall or partition structure, of a face finishing wall therefor, and vibration insulating means securing said finishing wall to said wall or partition structure and supporting the weight thereof.
25. In a building construction, the combination with an inner wall or partition structure, of a face finishing wall therefor, vibration insulating means securing said finishing wall to said wall or partition structure, and other vibration insulating means on which the said finishing wall independently rests.
26. In a building construction, the combination with an inner wall or partition structure, of a face finishing wall therefor, vibration insulating means securing said finishing wall to said wall or partition structure, and other vibration insulating means on which the said finishing wall independently rests.

nation with an inner wall or partition structure, of a face finishing wall therefor, vibration insulating means securing said finishing wall to said wall or partition structure, and vibration insulating supports independent of the said wall or partition structure on which the said finishing wall rests.

27. In a building construction, a partition structure including two face finishing walls, vibration insulating means securing said face walls in position and preventing solid contact between them, and a layer of vibra-

tion absorbing material between said face walls.

28. In a building construction, an inner 15 wall or partition structure, a face finishing wall therefor, vibration insulating means securing said face wall to said structure, and a layer of vibration absorbing material in the rear of said face wall. 20

In witness whereof, I have hereunto subscribed my name.

EVERETT N. MURPHY.
